ROPE

William L. Rochester, Manhasset, N. Y.

Application August 6, 1932. Serial No. 627,685

1 Claim. (Cl. 117—52)

The invention relates to rope and a method of producing same, and with respect to its more specific features, to strand construction of fiber rope of large diameter.

5 One object of the invention is to provide a practical and serviceable rope of greater strength in certain large sizes than has heretofore been possible according to previous constructions or by previously known methods of manufacture. 10 Another object of the invention is to provide a rope of great strength which will lie substantially "dead" when wet. Another object of the invention is to provide a rope which will be free of any tendency to untwist or rotate when suspending 15 heavy weights. Another object of the invention is to provide a rope in which internal friction is substantially eliminated. Another object of the invention is to provide a rope which will withstand hard usage. Other objects will be in part 20 obvious or in part pointed out hereinafter.

The invention accordingly consists in the features of construction, combinations of elements, arrangements of parts, and in the several steps and relation and order of each of said steps to 25 one or more of the others thereof, all as will be illustratively described herein, and the scope of the application of which will be indicated in the following claim.

In the accompanying drawing, in which is 30 shown one of various possible embodiments of the mechanical features of this invention,

Figure 1 is a view in elevation of a piece of rope, one end of which has been unraveled, and

Figure 2 is a cross-sectional view of the rope 35 shown in Figure 1, the several strands being sectioned in different planes.

Similar reference characters refer to similar parts throughout the several views of the drawing.

40 As conducive to a clear understanding of the present invention, I note that the usual rope has consisted of a great number of ends of yarn stranded together to form a strand, a plurality of strands being then twisted together to form the 45 rope. Such a rope of usual construction has a tendency to shrink when wet, kinking and becoming very difficult to handle, especially in the larger sizes, such as the heavy rope used for warping ships at a pier. It has been proposed to make 50 rope of yarns of uniform size, each strand being built up of a core laid in one direction and covering yarns laid in the opposite direction. Rope made in this manner, however, has been found to have lower tensile strength than rope of equal size 55 and grade of yarn of the ordinary construction,

owing to an excessive shearing action upon the covering yarns as they tighten and move against the core under strain.

Referring now to the drawing, rope according to the present invention is composed of a plurality of strands 10, 10, 10 twisted together. Considering now the construction of the strands 10, I take a plurality of slivers or hands 11 of manila fiber, for example, each one of which is relatively soft and loosely laid, that is having a small amount 60 of twist. The slivers or hands 11 are then loosely stranded together, that is with a small amount of twist, to form the core 12. By reason of the construction described, this core 12 is relatively soft. The diameter of the core 12 is preferably 65 substantially more than half the total diameter of the strands 10 of which it forms a part.

Still considering the formation of a single strand 10, I now cover the core 12 with covering yarns 13 which I lay onto the core 12 in a direction opposite to that of the twist or stranding of the core hands with respect to each other. These covering yarns 13 may be yarns of manila fiber and are relatively hard-twisted and have 70 great tensile strength. Preferably the twist of each yarn 13 is opposite to that of the lay of the 75 yarns 13 upon the core 12, and preferably the twist of fibers of the hands 11 is opposite to that of the lay of the slivers 11 with respect to each other. In the completed strand 10 the covering 80 14 which is composed of the several yarns 13, completely covers the core 12 and desirably 85 comprises two or more layers of yarns in cross-section as shown in Figure 2. The completed rope 15 90 desirably consists of three strands 10 twisted together in a direction opposite to that of the lay of the covering yarns 14 upon the core 12.

When the rope 15 is put under tension, the covering yarns 14 pull against the core 12, but 95 shearing action is avoided or reduced to a minimum because of the softness of the core 12. A material factor in increasing the strength of the rope lies in the fact that the core 12, being of relatively great diameter, that is to say more 100 than half the diameter of the strand 10, can undergo a great amount of compression. Another reason why the core 12 can undergo a great amount of compression is that the several hands thereof are loosely twisted together. Still another reason why the core 12 can undergo a 105 comparatively great amount of compression is that it consists of slivers, that is to say fibers that have undergone but a limited number of steps in the manufacture of yarn, for example 110 fibers that have been carded only. The strength

of the core 12 and the covering 14 is nicely balanced by the difference in cross-sectional area thereof.

When ordinary rope is subjected to a breaking strain the inner yarns part first due to their shorter length. By using for the core 12 hands or slivers 11 that are but slightly twisted and are capable of being stretched more than the relatively hard-twisted yarn 14 per unit length, the 10 total stretching capacity of the core is increased to compensate for the greater length of the yarn 14. As a result, when the rope of this invention is placed under a breaking strain, all parts of it reach the elastic limit at substantially the same 15 time, and accordingly the strength of the completed rope 15 for a given diameter is much greater than that of ordinary rope. This I have found to be the fact in practice.

The tendency of rope made according to the 20 present invention to twist and kink upon being wet is slight. Ordinary rope has a tendency to twist when wet, and in the case of hawsers for ships this is a serious disadvantage when the rope is new. In the construction of the present 25 invention, when the rope is wet, the core 12 tends to twist in one direction, and the covering 14 tends to twist in the opposite direction, and the two strains substantially neutralize each other. At the same time no shearing action is exerted 30 against the covering yarns 14 owing to the softness of the core 12.

It should be understood that in giving my 35 theory of why rope made according to the present invention has little tendency to twist or kink, and is stronger than ordinary rope, I give the best

explanation now known to me of these facts, the invention not being limited thereby as rope made according to the present specification has the characteristics noted whether the explanation is correct or not.

It will thus be seen that there have been provided by this invention an article and a method of manufacture in which the various objects hereinbefore set forth, together with many thoroughly practical advantages are successfully achieved.

As various possible embodiments might be made of the mechanical features of the above invention, and as the art herein described might be varied in various parts, all without departing from the scope of the invention, it is to be understood that all matter hereinbefore set forth or shown in the accompanying drawing is to be interpreted as being illustrative and not in a limiting sense.

I claim:

Manila rope comprising three strands twisted together in a given direction, each strand comprising a core and a plurality of yarns laid on the core in an opposite direction of twist, each 100 yarn being hard-twisted in the given direction, the core comprising a plurality of soft twisted hands twisted among themselves with slight twist in the given direction and the fibers of each hand being twisted together with a slight twist in the 105 opposite direction, the core being soft and having a diameter greater than half of that of the total strand.
